UNITED STATES PATENT OFFICE.

CHARLES E. OUILLETT, OF LOWELL, MASSACHUSETTS.

ELEVATOR.

1,392,078.

Specification of Letters Patent. Patented Sept. 27, 1921.

Application filed July 18, 1919. Serial No. 311,751.

To all whom it may concern:

Be it known that I, CHARLES E. OUILLETT, a citizen of the United States, residing at Lowell, in the county of Middlesex and State of Massachusetts, have invented certain new and useful Improvements in Elevators, of which the following is a specification.

This invention relates to elevators, and an object of the invention is to provide an elevator operating mechanism for raising and lowering the cage of the elevator, which does not employ cables, hydraulic columns or analogous structure, the prime mover or operator or elevating or lowering mechanism being carried beneath the bottom of the cage and receiving its power through suitable conductors carried by the upright beams of the elevator structure.

20 A further object of the invention is to provide a comparatively simple control for controlling the direction of movement of the cage.

A further object is to provide an elevator structure as specified which is comparatively simple in construction, and consequently may be installed at a relatively low cost, as well as one in which liability of accident due to the falling of the cage is eliminated, the means for transmitting the elevating or lowering movement to the cage being such that in case any part of the mechanism breaks, the said means will support the cage without any drop whatsoever, at the point at which 35 it was when the breaking occurred.

Other objects of the invention will appear in the following detailed description, taken in connection with the accompanying drawings, forming a part of this specification, 40 and in which drawings:

Figure 1 is a fragmentary vertical section through the elevator mechanism.

Fig. 2 is a fragmentary vertical section through the elevator mechanism taken at 45 right angles to the section illustrated in Fig. 1, and

Fig. 3 is a bottom plan of the elevator cage illustrating the operating mechanism therefor.

50 Referring more particularly to the drawings, wherein like characters indicate like and corresponding parts throughout the several views, 5 and 6 indicate the upright beams of the elevator structure which beams 55 have vertically extending racks 7 carried by their facing sides, with which racks worms

8 and 9 mesh for either elevating or lowering the elevator cage 10. The worms 8 and 9 are positioned one at each side of the cage 10 beneath the bottom or floor 11 thereof and they are mounted upon the shafts 12 and 13 respectively. The shafts 12 and 13 are rotatably supported by suitable hangers 14 which are suspended from the floor beams 15 of the cage structure 10. Worm gears 16 are mounted upon the upper ends of the shafts 12 and 13 and they mesh with worms 17 mounted on the opposite ends of the shaft 18. The shaft 18 is rotatably supported by suitable bearings 19 carried by cross beams 20 and it has sprockets 21 and 22 mounted thereon about which sprocket chains 23 and 24 travel. The sprocket chain 23 travels about a sprocket carried by the stub shaft 25, which stub shaft carries a gear 26 which 75 meshes with a gear 27 mounted upon the hub 28 of a clutch section 29. The clutch section 29 is rotatably mounted upon the main power shaft 30 of the prime mover or electrical motor 31, and is operatively connected 80 to said shaft for rotation thereby upon inter-engagement with the clutch section 32. The clutch section 32 is feathered upon the shaft 30 and has a shifting arm 33 connected thereto which is in turn connected to the 85 shifting rod 34. The provision of the gears 26 and 27 will rotate the shaft 18 in a direction reversely of the direction of rotation of the shaft 30 when the clutch sections 29 and 32 are in inter-engagement with each other. 90 The shaft 18 is rotated in the same direction in which the shaft 30 is rotated through the medium of the sprocket 22, chain 24, and sprocket 35. The sprocket 35 is mounted upon the hub 36 of a clutch section 37 which 95 is rotatably mounted upon the shaft 30 and is adapted for inter-engagement with a clutch section 38 feathered upon the shaft 30. A shifting arm 39 is connected to the feathered clutch section 38 and to the shifting rod 34 as clearly shown in Fig. 3 of the drawings. A shifting rod 34 has cables 40 and 41 connected to its opposite ends, and the cable 40 passes about a suitable sheaf or guiding pulley 42 and is connected to the 105 operating lever 43 upwardly of and to one side of the pivot thereof as shown at 44 in Fig. 2 of the drawings, while the cable 41 passes about a horizontal guiding sheaf or pulley 45, over the vertical sheaf 46 and is 110 connected to the lever 43 at a point upon the opposite side of its pivot from the point of

connection to the cable 40 and the lever, so that when the lever 43 is moved in one direction or to the left of Fig. 2 of the drawings, it will slack the cable 41 and tighten the cable 40 for shifting the rod 34 to move the clutch section 38 into inter-meshing engagement with the clutch section 37, and move the clutch section 32 away from the clutch section 29, while if the lever 43 is moved 10 in the opposite direction or to the right of Fig. 2 it will shift the rod 34 to move the clutch section 32 into meshing engagement with the clutch section 29 while the clutch section 38 is moved away from the clutch section 37, and thus by the shifting of the lever 43 the direction of movement of the elevator cage 10 is determined.

Electrical current conducting rails 47 and 48 are carried at the sides of the upright beams 5 and 6 respectively and contacting rollers 49 and 50 are yieldably supported at opposite sides of the elevator cage 10 and ride over the rails 47 and 48 respectively. Suitable conducting wires 51 and 52 are connected to the rollers 50 and to the opposed poles or terminals of the motor 31 for conveying the energizing current from the rails 47 and 48 to the motor to operate the latter for rotating the shaft 18 and from this shaft 30 the vertical stub shafts 12 and 13 which carry the worms 8 and 9. The rotation of these worms 8 and 9, will owing to their meshing engagement with the teeth of the racks 7, either elevate or lower the cage 10, 35 depending upon the direction in which the worms are rotated.

Suitable guards 53 are provided for the rails 47 and 48.

A housing 56 is attached to the bottom 40 of the cage 10 for inclosing the elevator operating mechanism, and it has one portion 57 hingedly connected as shown at 58 to the main body of the housing to permit access to the interior of the housing and consequently to the elevator operating mechanism. A chain or an analogous flexible device 59 is provided for limiting the opening movement of the door 57 of the housing.

Safety bumpers 60 are provided at the 50 bottom of the elevator pit, as is usual in elevator structures.

Changes in details may be made without departing from the spirit of this invention, but;

55 I claim:

1. In an elevator, the combination, of upright beams, racks carried by said beams, a cage, a pair of worms rotatably carried by said cage and meshing with said racks to 60 elevate or lower the cage upon rotation of the worms, an electric motor carried by said cage, a pair of clutches controlling the operative connection of said motor with said worms, a shifting rod connected to said

clutches, cables connected to said shifting 65 rod, a lever, said cables connected to said lever and movable parallel with the longitudinal run of the motor whereby said rod may be shifted by the pivotal movement of said lever for establishing operative communication between the motor and the worms.

2. In an elevator, the combination, of upright beams, racks carried by said beams, 70 a cage, a motor supported beneath said cage, an operating shaft for said motor extending therefrom on either side, a counter shaft, a series of gears connecting said counter shaft and said racks for establishing communication therebetween, means connecting 75 said counter shaft and said operating shaft upon one side of the motor for elevating the cage, and means connecting said counter shaft and said operating shaft upon the opposite side of said motor for lowering the 80 cage, said operating means being operable from within the cage.

3. In an elevator, the combination of upright beams, racks carried by said beams, 85 a cage, a motor supported beneath said cage, an operating shaft for said motor, said shaft projecting upon either side of said motor, a counter shaft, a series of gears establishing communication between said counter-shaft and said racks, means mounted 90 upon one side of said motor shaft for raising the elevator, means mounted upon the other side of said motor shaft for lowering the cage, and clutch elements shiftable longitudinally of the motor for operating 95 either the raising or lowering mechanism.

4. In an elevator, the combination, of upright beams, racks carried by said beams, a cage, a motor supported beneath said cage, an operating shaft for said motor projecting 100 upon either side thereof, a counter-shaft parallel with the longitudinal run of said motor, a series of gears establishing communication between the ends of said counter-shaft and said racks, means connecting said counter-shaft and said operating shaft upon 105 one side of the motor for raising the cage, and means for lowering the cage connecting the counter shaft and operating shaft upon the opposite side thereof, clutch elements 110 feathered upon said operating shaft, for operating either the raising or lowering mechanism, a shifting rod connected to said clutches, cables connected to said shifting 115 rod, said cables projecting upwardly through the floor of said cage, a lever pivotally connected upon the floor of said cage, said lever being adapted to be to one side for raising the elevator and to the other side for lowering the elevator, and means carried by said cage and beam for conveying current to the motor.

CHARLES E. OUILLETT.
